UNITED STATES PATENT OFFICE

1,953,743

WINDOW CONSTRUCTION

John S. Burrell, Great Neck, N. Y.

Application February 3, 1932, Serial No. 590,706

19 Claims. (Cl. 20—49)

This invention relates to a new and useful improvement in window construction and relates more particularly to a double hung sash type of window construction wherein the sashes are pivoted and adapted for rotative movement on a horizontal axis and are also adapted for vertical sliding movement as in the conventional type of sash construction.

One of the objects of the invention is to provide a window construction in which the sashes may be opened by vertical movement as well as by pivotal movement, thus enabling the dwelling or office in which the windows are placed to secure maximum ventilation when desired.

Another object of the invention is to provide a window in which the sashes have vertical sliding as well as pivotal movement and wherein the pivot members are interchangeable and may be placed near the top, bottom or in the center of the sash, the change being accomplished quickly and with little effort. Thus, in the summer time when screens are on the windows the pivots may be placed at the upper portion of the sash, enabling the sash to be "projected" rather than swung on a central pivot.

Another object of the invention is to provide a window construction of the type above referred to which will permit the outer surface of the glass to be quickly swung inwards, thus enabling it to be washed from the inside, thereby entirely eliminating the dangers incidental to outside window washing, eliminating the high insurance costs on professional window washers in tall buildings and, as well, encouraging the more frequent cleaning of windows in our smoke-ridden cities.

A further object of the invention is the provision of a window sash construction of this type which will provide weatherstripping means which make the sash rain and wind proof with tight closures at all joints.

The invention also has for an object the provision of a novel type of window construction, having one hundred per cent ventilation and means for inside window washing, and which is exceedingly simple in construction and may be produced in metal or in wood at a cost very little in excess of the cost of the old type of double hung sash construction.

The invention also contemplates the provision of a window construction which eliminates binding of the sashes and difficult manipulation of the window.

Other objects and advantages of the invention will be hereinafter specifically pointed out or will become apparent, as the specification proceeds.

With the above indicated objects in view, the invention resides in certain novel constructions, combinations and arrangements of parts, clearly described in the following specification and fully illustrated in the accompanying drawings, which latter show embodiments of the invention as at present preferred.

In the drawings:

Fig. 1 is a broken vertical section taken through one of the upper corners of the window box, the view also showing the pivotal support for one of the sashes.

Fig. 2 is a broken horizontal section taken through one side of the sashes and frame, the view showing the retractable weatherstrip guide and one means for disengaging same when the window is to be pivoted.

Fig. 3 is a vertical section taken substantially through the center of the entire window, the view also illustrating the possible horizontal position of the two sashes and their relative positions in the frame.

Fig. 4 is an enlarged broken vertical sectional view of the means for retracting the weatherstrip guides.

Fig. 5 is a broken horizontal section taken through one of the vertical portions of the sashes and shows the weatherstrip guide in a retracted position.

Fig. 6 is a broken horizontal section showing a modification in the construction of the embodiment.

Referring now to said drawings by reference numerals, the embodiment, as at present preferred, includes upper and lower sashes 10 and 11, respectively, which are mounted or hung in a window frame 12. The embodiment is adapted to be constructed of metal entirely or of wood and metal, the latter construction being illustrated in the drawings.

The sashes are of conventional construction, the upper one 10 including upper and lower rails 13 and 14 and side or vertical rails 15. The lower sash likewise includes upper, lower and side rails, 16, 17 and 18, respectively, each of the sashes carrying a window glass 19.

The lower rail 14 on the upper sash and the upper rail 16 on the lower sash are provided with conventional bevelled portions 20 and 21, respectively, and the lower edge of the lower rail 17 is bevelled inwardly.

Each vertical rail of the sash is provided with a longitudinal channel 23 on the outer edge thereof, a substantially U shaped channel member or liner 24 being secured within said channel by

means of screws 25. Within this liner a retractable combined weatherstrip and guide member 26 is supported, the weatherstrip member being constructed preferably of non-corroding metal and 5 being substantially H shaped in horizontal cross section. Any suitable, manually-operated means may be employed for moving the weatherstrip member inward and outward. I have heretofore with good results employed the following means. 10 I drill a substantially oval shaped aperture through each of the parallel portions of the weatherstrip member near the upper and lower portions thereof, the longer portion of each aperture being upright, as shown in Fig. 4. A horizontal shaft having a circular bearing portion 28, a non-circular central portion 29 and a reduced circular bearing portion 30, passes through each pair of apertures in the weatherstrip member and is journaled in the vertical portion 15 of the 15 sash. A pair of cam or eccentric members 31 are carried on the central or non-circular portion of the shaft and are spaced apart by means of a bushing 32, the cam members engaging the sides of the apertures 27 in the weatherstrip member, 20 as illustrated in Fig. 4. Thus, as the shaft is revolved by turning a handle 33, the weatherstrip member is caused to move inwardly or outwardly.

The inwardly facing vertical portion or jamb 36 of the frame is provided with a pair of channels 37, in which are secured a pair of metal trackways 38, one for each sash. The trackway has a pair of outer longitudinal grooves 39 into which the weatherstrip guide passes, and a central and wider groove 40 which acts as a guide for a pivot 41 secured in each of the vertical rails of the sash, the pivot passing through suitable holes in the liner 24 and in the weatherstrip member 26. In the drawings I have placed this pivot member 40 midway between the upper and the lower portions of the sash. It is obvious, however, that a plurality of pivot apertures may be provided in various positions on the vertical rails of the sash in order that when it is desired to project the 45 sash, i. e., pivot it from the top, in order not to interfere with a fixed screen on the window, the pivot members may be removed from the central apertures and placed in the top.

At the upper end of the frame, on each side 50 thereof, a pair of conventional pulleys 43 are mounted on a shaft, a chain 44 passing thereover. A sash weight 45 is secured to one end of the chain and the opposite end may carry a collar which fits over the outer end of the pivot. The sash chain 55 is preferably long enough to accommodate the pivot member when the latter is inserted in a lower pivot aperture, as stated above. When the pivot members are changed the only other necessary change is to increase or decrease the length 60 of the pulley chain.

When it is desired to insert the sash in the frame the sash may be held horizontally, raising one side thereof slightly in order to provide a clearance for the pivot members which are then 65 inserted in the central grooves in the trackways in each side of the frame. The sash may then be swung vertically and the weatherstrip guides moved outward into the outer grooves in the trackway.

70 In Fig. 6 I have illustrated a modified form of the construction of the embodiment wherein the weatherstrip guide is retracted into the channel in the frame rather than into the sash. In this figure I have designated the vertical rail of the 75 sash as 18', the jamb as 36' and the pivot as 41'.

On the outer surface of the vertical rail of the sash I provide a longitudinal groove 50 and I secure therein a channel bar 51 constructed preferably of sheet metal and having a channel portion 52 substantially rectangular in horizontal cross section. In the jamb I likewise provide a somewhat deeper groove 53 in which is secured another channel bar 54 having a deeply recessed channel 55. I then mount a U shaped channel 56 within the recess 55 and provide means, as in the preferred embodiment, for moving it outwards, as shown in the drawings, and also retracting it. In either position the channel 56 acts as a guide for the pivot member 41'. When it is in an outward position it engages the parallel sides of the channel bar 51, as shown, functioning both as a guide for the sash as well as for a weatherstrip.

Considerable particularities of description as to materials, part details, capacities and utilities may have been herein indulged in, but it will be understood that these statements, made with reference to those two of the many possible embodiments of the invention which are illustrated in the drawings, are not in any way to be taken as 100 definitive or limitative of the invention. Inasmuch as many apparently widely different embodiments of the invention could be made without departing from the scope thereof, it is intended that all matter contained in the above 105 description or shown in the accompanying drawings shall be interpreted as illustrative, and not in any limiting sense.

It is also to be understood that the language in the following claims is intended to cover all the 110 generic and specific features of the invention herein described, and all statements of the scope of the invention which, as a matter of language, might be said to fall therebetween.

In other words, the scope of the invention as 115 contemplated is to be taken solely from the appended claims, interpreted as broadly as is consistent with the prior art.

What I claim is:

1. A device of the class described including a 120 window frame, a plurality of sashes hung therein and means for providing pivotal and vertical sliding movement thereof, said means including a retractable weatherstrip member on each side of the structure for each sash, longitudinal grooves in 125 which said weatherstrip members reside, slidable pivot means for each sash, and means for engaging the pivot means with the sash at spaced points along the edges thereof.

2. A device of the class described including a 130 window frame, a plurality of sashes hung therein and means for providing pivotal and vertical sliding movement thereof, said means including a pivot member on each side of the sash, means for supporting the pivot members in a plurality of 135 positions, metal trackways having grooves and cooperating retractable metal weatherstrip guides adapted to pass into said grooves to maintain the sashes in a vertical position, said pivot members passing through and being independent of the 140 weatherstrip members.

3. A device of the class described including a window frame, a plurality of sashes supported therein and means for providing pivotal and vertical sliding movement of the sashes, said means 145 comprising a pair of metal trackways in each upright portion of the frame, said trackways having a plurality of longitudinal grooves therein, the vertical rails in each sash having longitudinal grooves therein, horizontal pivot members ex- 150

- tending outwardly from each vertical rail of the sash and adapted to pass into one of the grooves in each trackway, a sash supporting device secured to each pivot member, a weatherstrip member mounted within each of said grooves and adapted to pass outward to engage the grooves in the trackways, said weatherstrip members being mounted independently of the pivot members. 5
4. A device of the class described including a window frame and a plurality of sashes supported therein, and means for providing pivotal and vertical sliding movement thereof, said means including a pair of vertical trackways in each vertical portion of the sash, said trackways having a pair of narrow parallel grooves near the outer edges thereof and a wider groove in the central portion thereof, the vertical rails of each sash having a vertical groove therein, a liner secured in each groove, a horizontal pivot member extending outwardly from each vertical rail of the sash and adapted to pass into the central groove in the trackway, a sash cord secured to each pivot member and adapted to support same, an H shaped weatherstrip member mounted within said groove and means for moving the member outwards to engage the outer grooves in the trackway and for retracting the member into the groove in the sash and flush with the face of the rail. 10
5. In a double-hung window construction including a sash structure and a frame structure, opposed grooves formed along the sides of each of said structures, members carried with one of said structures and extending along substantially the full length of said sides, each of said members normally lying in both of the opposed grooves at a side of said sash and forming weather stripping, means to retract said members into the grooves in one of said structures to permit the sash to swing, and means providing pivots for said sash engaging the same and extending into the opposed grooves in the frame structure, the ends of said pivots being guided between vertical guides irrespective of the position of the weatherstripping. 15
6. In a double-hung window construction including a sash structure and a frame structure, opposed grooves formed along the sides of each of said structures, members carried with one of said structures and extending along substantially the full length of said sides, each of said members normally lying in both of the opposed grooves at a side of said sash and forming weather stripping, means to retract said members into the grooves in one of said structures to permit the sash to swing, said means being adapted to align the members parallel to the edge of the sash, means providing pivots for said sash engaging the same and extending through said weatherstripping members into the opposite grooves in the frame structure, the ends of said pivots being guided between vertical guides irrespective of the position of the weatherstripping, whereby a sash may be pivoted and slid simultaneously and means for supporting the sash through said pivot means. 20
7. In a double-hung window construction including a sash structure and a frame structure, opposed grooves formed along the sides of each of said structures, members carried with said sash and extending along the sides thereof, each of said members normally lying in both of the opposed grooves at a side of the sash and forming weather stripping along the entire sides thereof, means carried with said sash and adapted to retract said members into the grooves in the sash, to permit the stripping to swing with the sash, and pivot members for said sash engaging the same and extending into the opposed grooves in the frame structure, said pivots being guided between vertical guides irrespective of the position of the weatherstripping. 25
8. In a double-hung window construction including a sash structure and a frame structure, opposed grooves formed along the sides of each of said structures, metal members carried with said sash and extending along the sides thereof, each of said members normally lying in both of the opposed grooves at a side of the sash and forming weather stripping along the entire sides thereof, means carried with said sash and adapted to retract said members into the grooves in the sash, to permit the stripping to swing with the sash, and pivot members for said sash engaging the same and extending into the opposed grooves in the frame structure, said weatherstripping members being adapted to lie adjacent the side walls of the grooves to act as guides for the sash and to form double weather stripping, and said pivot members extending through openings formed in the stripping members and being attached to means to support the sash, the ends of said pivots being guided between vertical guides irrespective of the position of the weatherstripping, whereby a sash may be pivoted and slid simultaneously. 30
9. In a double-hung window construction including a sash structure and a frame structure, opposed grooves formed along the sides of each of said structures, members carried with one of said structures and extending along said sides, each of said members normally lying in both of the opposed grooves at a side of said sash and forming weather stripping, means to retract said members into the grooves in one of said structures to permit the sash to swing, said means being adapted to align the members parallel to the edge of the sash, detachable pivot members, means formed in said sash for engaging said pivot members at a plurality of points at either side of the sash, and means to support the sash connected directly to the pivot members, said pivot members being adapted to extend into opposed grooves in the frame structure. 35
10. A device of the class described including a window frame, a sash slideable therein, pivot pins, a plurality of spaced means carried with the vertical rails of said sash for engaging said pins at a plurality of spaced points along the lengths of said rails, vertical grooves formed in said frame to receive the free ends of the pivot pins, grooves in said rails opposed to the first-named grooves, means for supporting the sash attached to said pivot pins, and weatherstrip members at least as long as the sash and receivable in the grooves in the frame, said members being adapted normally to extend into the grooves in the rails and being retractable within the grooves in the frame to permit the sash to pivot about the axis of said pins. 40
11. In a double-hung window construction including a frame and a sash, in combination, a pivot member on each side of the sash, means including metal trackways on opposite sides of the sash and opposed metal trackways in the frame, said trackways forming opposed grooves, metal weatherstrip members adapted to lie in said opposed grooves at each side of the sash, to maintain the same in sliding relation with respect to the frame, and means to retract the weatherstrip 45

members into the grooves in certain of said trackways to permit the sashes to swing about the axis of said pivot members, said pivot members passing through and being independent of the weatherstrip members.

12. In a double-hung window construction including a frame and a sash, pivot members secured in opposite sides of the sash, opposed grooves formed in the side rails of the sash and opposite portions of the frame, a metal liner in each of said grooves, retractable, generally U-shaped metal members lying in said opposed grooves at opposite sides of the sash and frame, said U-shaped members being at least as long as the sash, and means for moving said U-shaped members into certain of said grooves to permit the sash to swing about the axis of the pivot members, said pivot members extending through said U-shaped members into the grooves in the frame.

13. In a double-hung window construction including a sash structure and a frame structure, opposed grooves formed along the sides of each of said structures, members carried with one of said structures and extending along said sides, each of said members normally lying in both of the opposed grooves at a side of said sash and forming weatherstripping by engagement with the side walls of the grooves, means to retract said members into the grooves in one of said structures to permit the sash to swing, and pivot members engaged with said sash and extending into the grooves in the frame structure in sliding relation therewith irrespective of the position of the weatherstripping members, the ends of said pivot pins being engaged at either side to prevent a substantial lateral motion of the pins when the weatherstripping members are retracted, whereby said sash may be moved vertically and simultaneously pivoted.

14. In a construction of the character described including a window frame and a slidable sash, pivot members carried by the sash and extending into the frame, said pivot members being constantly in position for pivoting the sashes, opposed longitudinal grooves formed in the frame and sash, a cooperating weatherstrip member at each side of the sash extending the full length thereof and normally lying partly in a groove in the frame and partly in a groove in the sash, each of said weatherstrip members being adapted to be retracted substantially entirely within one of said grooves and being operable independently of said pivot members, and means to retract said weatherstrip members into one of said grooves to permit the sash to tilt.

15. In a construction of the character described, including a window frame and double-

hung sashes therein, opposed grooves formed in the side rails of the sashes and in the frame, weatherstrip members extending the full length of each sash, and normally lying partly in the groove in the sash and partly in the groove in the frame, and means to retract each of said weatherstrip members into one of said grooves, and pivot members carried rigidly with said sash, said weatherstrip members being constructed and arranged to operate independently of the pivot members but at the same time to act as a guide for the pivot members.

16. In a construction of the character described, including a window frame and double-hung sashes therein, opposed grooves formed in the side rails of the sashes and in the frame, weatherstrip members extending the full length of each sash, and normally lying partly in the groove in the sash and partly in the groove in the frame, means to retract each of said weatherstrip members into one of said grooves, and pivot members carried with said sash, said weatherstrip members being constructed and arranged to operate independently of the pivot members but at the same time to act as a guide for the pivot members, and means to support each of said sashes through connections with said pivot members.

17. In combination with a frame and double-hung sashes therein, said frame and sashes having opposed vertical grooves including metal walls, metal weatherstrip members adapted to form contact with side and rear walls of certain of said grooves and extending the full length of each sash, said weatherstrip members normally lying partly in each groove, and each member being capable of being moved wholly into one of said grooves, pivot members carried with said sashes independently of said weatherstrip members, and means to support said sashes through connections with said pivot members.

18. The combination as claimed in claim 17, wherein means are provided for receiving said pivot members at a plurality of spaced points in the side rails of the sashes.

19. In combination with a frame and double-hung sash therein, both frame and sashes having opposed grooves lined with metal, on their vertical contacting surfaces, a two-point contact weatherstrip member the full length of each sash, normally lying partly in each groove, but capable of being moved wholly into one of said grooves when not acting as a guide for vertical movement, said weatherstrip member to be independent of but to act as a guide for the pivot members.

JOHN S. BURRELL.
